UNITED STATES PATENT OFFICE.

JEROME T. McGONIGAL, OF POTTERSDALE, PENNSYLVANIA.

COMBINATION RAILWAY-TIE AND CLAMP.

1,073,773.

Specification of Letters Patent. Patented Sept. 23, 1913.

Application filed July 19, 1913. Serial No. 780,046.

To all whom it may concern:

Be it known that I, JEROME THOMAS McGONIGAL, a citizen of the United States, residing at Pottersdale, in the county of Clearfield and State of Pennsylvania, have invented a new and useful Combination Railway-Tie and Clamp; and I do hereby declare the following to be a full, clear, and exact description of the invention, such as will enable others skilled in the art to which it appertains to make and use the same.

This invention relates to a new and useful combination railway tie and clamp.

As an object of the invention it is the aim to provide a tie, each end of which on its under surface is so constructed or hollowed out, so as to maintain the proper position.

A feature of the invention is to provide a tie, preferably constructed of metal, the central under surface of which is rounded so as to permit the central portion of the tie to slightly yield or bend upwardly, and the ends of the tie pressed downwardly 25 against the ballast, as the wheels of a train pass over the rail.

Another feature of the invention is the provision of a tie having two sets of teeth, each set to be engaged by teeth of a rail plate which supports a rail. As a rule, the rails are vertical. But sometimes, however, the rails become outwardly turned or inclined from one another, thereby causing the car wheels to run on the inside of the 35 rails, and in this case the rail plates are provided with inclined surfaces as shown in Figs. 1 and 5.

In practical fields the details of construction may necessitate alterations, to which 40 the patentee is entitled, provided the alterations fall within the scope of what is claimed.

The invention comprises further features and combination of parts, as hereinafter set forth, shown in the drawings and claimed.

In the drawings:—Figure 1 is a view in perspective of the improved tie constructed in accordance with the invention. Fig. 2 is a sectional view. Fig. 3 is a transverse 50 sectional view on line 3—3 of Fig. 2. Fig. 4 is a sectional view on line 4—4 of Fig. 2. Fig. 5 is a detail view of one of the rail supporting plates.

Referring more particularly to the drawings, 1 designates the railway tie, which may be constructed of any suitable metal.

The central portion 2 of the tie is made thinner than the end of the tie, and in cross section the central portion of the tie upon its under surface is rounded, and designated by the character 3, thereby preventing the tie from gathering a central solid foundation. The under surface of the tie at each end is arched, so as to receive and hug closely to the ballast or the road bed. The purpose of this arched under surface 3^a of the tie is to prevent creeping. The purpose for rounding the central portion of the tie on its under surface is to permit of a slight flexibility of the tie in the direction of the rails, or in other words, a slight rocking of the tie.

By constructing the under surface of the tie at each end arched like, as shown at 3^a, the derangement of the ballast and the road bed is considerably obviated. Furthermore, the entire length of the tie is constructed hollow, as designated by the character 5.

The ends of the tie upon its upper surface are provided with corrugations 7, which are engaged by the corrugations 8 of the rail plates 9, on which and between the shoulders 10 of the rail plates the bases of the rails engage. These rail plates are secured in position by spikes 11, the lower ends of which are round or cylindrical, and pass through tubes 12, there being nuts 13 to secure the spikes in position. The portions of the spikes adjacent their heads are rectangular in cross section, so as to prevent turning of the spikes, which also pass through the tie. As a rule, the surfaces 14 of the rail plates on which surfaces the rails rest, are substantially horizontal, thereby holding the rails vertically. However, sometimes the rails become outwardly turned or inclined from one another, owing to the downward movement of the outer end of the tie, thereby causing the car wheels to sometimes run on the inside of the rails, and in this case, rail plates having their surfaces 14 inclined as shown in Figs. 1 and 5 are substituted, thereby throwing the rails toward one another, so as to cause the car wheels to run upon the center of the rails. When the end portions of the tie move downwardly, the central portion of the tie bows or yields upwardly.

The invention having been set forth, what is claimed as new and useful is:

1. A railway tie comprising an elongated body, the under surfaces of which at its

ends are arched upwardly, while its central portion is contracted and constructed circular on its under surface in cross section, thereby permitting the outer ends of the tie 5 to move downwardly while the central portion bows upwardly incident to weight thereon.

2. A railway tie having concaved under surfaces at its ends and provided with a 10 contracted convexed central portion, which permits the end portions to move downwardly while the central portion bows or yields upwardly.

3. A railway tie having concaved under 15 surfaces at its ends and provided with a contracted convexed central portion, which permits the end portions to move downwardly while the central portion bows or yields upwardly, said tie having its end 20 portions hollow.

4. A railway tie having concaved under surfaces at its ends and provided with a contracted convexed central portion, which permits the end portions to move downwardly while the central portion bows or 25 yields upwardly, said tie having its end portions hollow, the upper surface of the tie being constructed with means at each end for holding the rails inclined toward 30 one another normally.

5. A railway tie having concaved under surfaces at its ends and provided with a contracted convexed central portion, which

permits the end portions to move downwardly while the central portion bows or 35 yields upwardly, and rail plates mounted on the tie having their upper surfaces inclined downwardly and toward one another, to hold the rails inclined toward one another normally, said tie having its end portions 40 hollow.

6. A railway tie having concaved under surfaces at its ends and provided with a contracted convexed central portion, the 45 concaved under surfaces constituting means to prevent derangement of the ballast and the road bed, while the convexed central portion acts to permit flexibility of the tie and a slight rocking of the same in the direction of the rails, the entire length of the tie 50 being hollow, the upper surface of the tie having corrugations adjacent each end, rail plates having corrugations to engage the corrugations of the tie, said tie having tubes embedded therein, and means engaging the rail plates and the rails and entering said tubes for holding the plates and the rails in position.

In testimony whereof I have signed my name to this specification in the presence of 60 two subscribing witnesses.

JEROME T. McGONIGAL.
